Application June 5, 1935, Serial No. 25,026
 Renewed December 21, 1937

13 Claims. (Cl. 250—20)

This disclosure relates to a frequency or phase modulation receiver wherein the received energy is frequency multiplied and thence converted to amplitude modulation by means of a frequency modulation conversion circuit. The resulting amplitude modulation in the output of the conversion circuit is detected in the usual way if frequency modulation is being received. If phase modulation is being received, equalization may be applied to correct for the inherent frequency distortion.

An object of this invention is to provide a simple receiver for the purpose of detecting and tracing extraneous or unwanted frequency or phase modulation on a modulated transmitter. By applying frequency multiplication plus heterodyning to the received energy the depth of frequency or phase modulation is multiplied by the order of the frequency multiplication so that the receiver may be made ultra-sensitive and more suitable for working with low degrees of modulation. This feature is especially valuable in the case of low modulation frequency or phase modulation where the effective degree of frequency modulation is low and the frequency modulation converting circuit is insensitive to these modulations.

The present receivers available for detecting phase modulation are usually considerably complicated whereas frequency modulation receivers are fairly simple. Phase modulation may be received on a frequency modulation receiver, but the inherent difference between frequency and phase modulation makes the output of a frequency modulation receiver, receiving phase modulation, directly proportional to frequency. Consequently, the receiver would be insensitive to the low modulation frequencies of phase modulation. Equalizing circuits may be applied to the detected energy of this type of a receiver to correct for the frequency distortion. However, in cases where unwanted modulations are being traced, equalization is unnecessary. The receiver of this invention then proves valuable.

An advantage of the principles disclosed in this invention is that by using this frequency multiplication plus heterodyning system, the requirements of the frequency modulation converting circuits do not have to be so exacting and receiver design is facilitated. Thus a frequency multiplication of two might be employed in order to reduce the length of the artificial line or retard circuit in the artificial line type converting circuit, to one half.

A further novel feature of this invention is one of its means for producing frequency multiplication. By utilizing the higher order effects of a power law detector, a harmonic of the signal is caused to heterodyne with a harmonic of the local oscillator so that the resulting output is the same as though the intermediate frequency energy were

passed through a harmonic generator or frequency multiplier. In this manner the separate harmonic generator is dispensed with and the change from one order of frequency multiplication to another is effected by merely tuning the local oscillator. Where a separate frequency multiplier is used, the change of order of multiplication requires the tuning of several stages.

The novel features of my invention have been pointed out with particularity in the claims appended hereto, as required by law. The nature of my invention and the manner in which the same operates will be understood from the following detailed description thereof and therefrom when read in connection with the attached drawings through which like reference characters indicate like parts insofar as possible, and in which:

Figs. 1 and 2 each illustrate different modifications of wave receiving means arranged in accordance with the principles of my invention.

In Fig. 1, the intermediate frequency energy resulting from the heterodyne detector is frequency multiplied to increase the depth of modulation and the modulations are converted in a novel circuit into modulations of a different character for demodulation.

In Fig. 2, the depth of modulation is increased by harmonic action of the heterodyne demodulator and the resulting energy is converted and demodulated.

Figs. 3 and 4 are characteristic curves, illustrating the operation of the demodulator and harmonic generating tube in the circuit of Fig. 2; while

Figs. 5, 6 and 7 are graphs illustrating the operation of the demodulating means in the circuit of Fig. 1.

The circuit of Fig. 1 shows one form of the receiver wherein a separate frequency multiplier is used. The signal from antenna 1 is amplified in radio frequency amplifier 2 and heterodyned to intermediate frequency by means of detector 3 and high frequency oscillator 4. Intermediate frequency amplifier 5 amplifies and filters the intermediate frequency energy. The intermediate frequency energy is then passed through the frequency multiplier 6 where it is multiplied the desired number of times. By means of detector 7 and intermediate frequency oscillator 8, the multiplied energy is heterodyned to a lower frequency which is more suitable for filtering in the frequency modulation demodulator coupled to 10. This demodulator may be any type of frequency modulation converting circuit—that is, a circuit capable of translating frequency modulated energy to its signal energy. For example, the output of the intermediate frequency amplifier may be fed to the primary winding of transformer 10, the secondary winding of which is coupled to control electrodes in tubes 12 and 14, as shown. The

output of tube 12 is filtered by filter sections 15 and 16 and the filtered energy is then fed to the control grid of a detector tube 17 and also to the control grid of a combining tube 13. The 5 output of tube 14 is combined with the output of tube 13, through the impedance coupling 22. A potentiometer 23 controls the volume of the energy supplied from the filters 15, 16 to the tube 13. Potentiometer 21 regulates the voltage 10 supplied from the impedance coupling 22 to the control grid of detector tube 18, so that this energy is equal to the energy that is fed from 15, 16 to the control grid of detector tube 17. Transformer 19 combines the audio outputs of 15 the detectors 17, 18. The combined signal appears in an indicating or recording device 20 either directly from the secondary winding of 19 or by way of a filter circuit, depending upon the position of switch 26. Switch 24 regulates the 20 phase of combination of the audio outputs of the two detectors. When frequency modulated waves are received, the outputs of tubes 17 and 18 are connected in push-pull relation. By reversing switch 24 to connect the outputs of tubes 25 17 and 18 in parallel, amplitude modulated waves may be received.

The principle of the operation of a back-to-back type of frequency modulation receiver requires that one detector be fed by the signal 30 passed through a filter of positive slope, as shown in Fig. 5, and the other detector by a filter of negative slope, as shown in Fig. 6. Ordinarily, two filters having these slopes are built separately. However, by combining a filter of one slope with 35 a filter of flat top characteristic, as shown by Fig. 7, a filter of opposite slope may be obtained. For instance, the output of the filter of Fig. 6 may be subtracted from the output of the filter of Fig. 7 and the resultant would be a negative 40 slope filter, as shown by Fig. 5. In this manner, the output of the filter 15, 16 in Fig. 1 may be given by Fig. 6, for f_c as the carrier frequency and f_0 , f_1 , the band limits. The output of tube 45 14 is an aperiodic amplification of the signal giving a flat top characteristic, like that of Fig. 7, although not necessarily a bandpass action, as Fig. 7 portrays. (In Figs. 5, 6 and 7, the characteristics are assumed to be ideal, so that the filters cut off at the outer limits of the received 50 wave band; in the actual case this would only be approximated.) The combination of the outputs of tubes 13 and 14 is in reality a subtraction of the characteristics of Fig. 6 from that of Fig. 7, so that Fig. 5 is obtained, thus, the slope of the 55 filter has been reversed. Thus, feeding the output of the filter 15, 16 directly to one detector tube, say 17, and reversing the slope for the other detector, say 18, gives the equivalents of two filters and a back-to-back action. Tubes 13 and 14 60 then merely function to apply the output of the one filter with its slope reversed to the detector 18. The inputs to the two detectors are balanced by means of the potentiometer 21.

For the reception of phase or frequency modulation, the use of opposite slope demodulating filter effects applied from 15, 16 to 17 and from 65 22 to 18 causes the resulting two amplitude modulations fed from the outputs of detectors 17 and 18 to be 180° out of phase. To make the detected outputs add, they are combined in the transformer 19 with the series of push-pull connections to produce an 180° reversal of phase of one output. In the case of amplitude modulation, however, the phase of the modulation is 70 unaffected by the demodulating filters and the 75

parallel connection of transformer 9 is used. A similar converting and demodulating system has been described in detail and claimed in my U. S. application Ser. No. 703,770, filed Dec. 23, 1933, Patent No. 2,061,611, November 10, 1936.

Thus, it is seen that the signal is received on a superheterodyne receiver, units 1, 2, 3, 4 and 5 and is frequency multiplied to a higher frequency so that the depth of its phase or frequency modulation is multiplied. This higher depth modulation is then heterodyned down to a lower frequency which is more suitable for receiving on a filter-type frequency modulation receiver. The first intermediate frequency voltage is given by:

$$e = E \sin (wt - \phi \cos pt) \quad (1) \quad 15$$

where $w = 2\pi x$ intermediate frequency, f, ϕ = phase deviation in the case of phase modulation or $\phi = fd/fm$, where fd = frequency deviation and fm = modulation frequency, in the case of frequency modulation $p = 2\pi fm$. Hence the equation covers both phase and frequency modulation, depending upon whether ϕ indicates phase deviation or modulation index, fd/fm . In this respect, the following analysis is general—that is, it covers both the frequency modulation and phase modulation cases.

It is known to the art that after passing the intermediate frequency voltage through the frequency multiplier, the result is:

$$e = E \sin N(wt - \phi \cos pt) \quad (2) \quad 30$$

$$e = E \sin (2\pi Nft - N\phi \cos pt) \quad (3)$$

where N is the order of frequency multiplication. It is seen from (2) and (3), that f as well as ϕ are multiplied by N ; consequently, the frequency as well as the depth of modulation are both multiplied.

This multiplied energy is then heterodyned from its frequency Nf to a third intermediate frequency which is suitable for filtering; the result is:

$$e = E \sin (2\pi f_1 t - N\phi \cos pt) \quad (4) \quad 40$$

Equation (4) shows that the energy has been converted from a frequency f of (1) with a depth of modulation of ϕ to a frequency f_1 with a depth of modulation of $N\phi$. Consequently, the depth of modulation of all the modulating frequencies has been increased. As a result, the sensitivity of the receiver has been increased sufficiently so that a frequency modulation converting circuit may be used for the reception of phase modulation, especially on the lower modulation frequencies of phase modulation. The fact that the output of a frequency modulation receiver, which receiving phase modulation, is directly proportional to frequency may best be pointed out by differentiating the phase of (4) to obtain the instantaneous frequency of the wave.

$$f(\text{radians/sec}) = \frac{d(2\pi f_1 t - N\phi \cos pt)}{dt} \quad (5)$$

$$f(\text{cycles/sec}) = f_1 + fmN\phi \sin pt \quad (6) \quad 65$$

In the case of frequency modulation $\phi = fd/fm$ so

$$f = f_1 + Nfd \sin pt \quad (7)$$

Consequently, if (7) is linear and faithful to the signal of modulation on a frequency modulation receiver, a wave with an instantaneous frequency given by (6) would produce an output proportional to fm , the modulation frequency. For this reason, the principle of frequency multiplication 70 75

at the receiver becomes valuable for the lower modulation frequencies of phase modulation.

The circuit of Fig. 2 is an adaptation of the higher order effect type of detector and frequency multiplier, and a long line type of frequency modulation converting circuit. The radio frequency amplifier 2 fed by antenna 1 feeds the control grid G1 of the pentode detector 3. The suppressor grid G2 of tube 3 is fed by energy 5 from the high frequency oscillator 4. The oscillator 4 may be tuned so that fundamental energy therefrom beats with the harmonic of the signal carrying wave energy or may be tuned so that a harmonic of the fundamental wave of the oscillator beats with a harmonic of the fundamental signal carrying wave energy. The frequency multiplied and heterodyned output of detector 3 is fed to the intermediate frequency amplifier 5 where it is amplified and filtered. The 10 output of 5 is fed to the grids of detectors 28 and 29 via transformer 27 which has an astatic shield 35. It is also fed via line 26 to the detector grids through the midtap of 21. The output of detectors 28 and 29 is resistance coupled to audio amplifiers 30 and 31 and translated by phones 20. The frequency modulation conversion circuit 15 from 5 on is essentially the same as Fig. 3 of my U. S. Appln. Ser. No. 618,154, filed June 20, 1932.

In the Fig. 2 circuit, the signal energy is fed 20 to the control grid of the pentode detector, and the high frequency oscillator energy to the suppressor grid. By adjusting these two grids so that they operate on the non-linear portion of their dynamic characteristics, a harmonic of the 25 signal may be heterodyned by a harmonic of the local oscillator to produce an intermediate frequency. The resultant effect is then the same as though the signal had been frequency multiplied by means of a separate frequency multiplier, and heterodyned to the intermediate frequency by means of an intermediate frequency oscillator. The manner in which the pentode detector acts to produce this type of frequency multiplying is most easily explained by the following mathematical analysis:

The curves of Figs. 3 and 4 show the plate current-control grid voltage ($I_p = E_{g1}$) and plate current suppressor grid voltage ($I_p = E_{g2}$) characteristics for a pentode detector. It is well 30 known that the varying current in the output of the detector, due to a single grid, may be expressed as a function of the sinusoidal voltage impressed upon the input by the power series:

$$J = a_1 e + b_1 e^2 + c_1 e^3 + \dots \quad (8)$$

The output due to two grids will be given by:

$$J = (K_1 E_{g1} + a_1 e_1 + b_1 e_1^2 + c_1 e_1^3 + \dots) + (K_2 E_{g2} + a_2 e_2 + b_2 e_2^2 + \dots) \quad (9)$$

Multiplying (9) out and eliminating all but the 40 terms causing beats or a heterodyne output:

$$J = \left[\begin{array}{l} \underbrace{a_1 a_2 e_1 e_2}_{(1)} + \underbrace{b_1 a_2 e_1^2 e_2}_{(2)} + \underbrace{c_1 a_2 e_1^3 e_2}_{(3)} + \\ \underbrace{a_1 b_2 e_1 e_2^2}_{(4)} + \underbrace{b_1 b_2 e_1^2 e_2^2}_{(5)} + \underbrace{c_1 b_2 e_1^3 e_2^2}_{(6)} + \\ \underbrace{a_1 c_2 e_1 e_2^3}_{(7)} + \underbrace{b_1 c_2 e_1^2 e_2^3}_{(8)} + \underbrace{c_1 c_2 e_1^3 e_2^3}_{(9)} + \dots \end{array} \right] \quad (10)$$

From (10) it can be seen that term (1) will produce beats between the fundamental of the signal applied on one grid, say G1, and the fundamental of the local oscillator applied to the other grid, say G2. When the detector is adjusted for 45 normal detection, without frequency multiplica-

tion, co-efficients a_1 and a_2 are made large compared to b_1 b_2 , c_1 c_2 , etc., by adjusting the grid biases so that the signal and oscillator swing over the linear portion of the tube characteristics as the point "a" in Figs. 3 and 4.

Terms (5), (9), etc., are the higher order terms which produce the frequency multiplication. Term (5) is the product of the squares of the signal and local oscillator which produces the beat between the second harmonic of the signal and the second harmonic of the oscillator. In the same manner term (8) produces the beats between the third harmonics. The remaining terms (2), (3), (4), (8), etc., all contribute fundamental and harmonic beats but to a lesser degree than (1), (5), (9), etc. Thus, it can be seen that, to operate the detector as a frequency multiplying detector, coefficients b_1 , b_2 , c_1 c_2 , etc., must be made as large as possible. This is done by operating with the grid biases at the curved portion 50 of the characteristics as at "b" of Figs. 3 and 4. Also the output is an exponential function of the two input voltages so that the input voltages must be made high compared to their normal detection values; that is, the detector should be 55 overloaded.

In order to show how term (5) produces a beat between the second harmonic of the signal and the second harmonic of the oscillator, the signal of equation (1) will be applied as e_1 of one grid 60 and a local oscillator

$$e_2 = E_0 \sin \omega t \quad (11)$$

on the other grid. Term (5) of 10 is:

$$J = b_1 b_2 e_1^2 e_2^2 \quad (12) \quad 35$$

$$J = b_1 b_2 E^2 \sin^2(\omega t - \phi \cos \omega t) E_0^2 \sin^2 \omega t \quad (13)$$

$$J = b_1 b_2 E^2 E_0^2 \left(\frac{1}{2} - \frac{1}{2} \cos 2(\omega t - \phi \cos \omega t) \right) \left(\frac{1}{2} - \frac{1}{2} \cos 2\omega t \right) \quad (14) \quad 40$$

Multiplying and separating out the heterodyne term:

$$J = \frac{b_1 b_2 E^2 E_0^2}{4} (\cos 2(\omega t - \phi \cos \omega t) \cos 2\omega t) \quad (15)$$

$$= \frac{b_1 b_2 E^2 E_0^2}{8} (\cos((2\omega t + 2\phi) - 2\phi \cos \omega t) + \cos((2\omega t - 2\phi) - 2\phi \cos \omega t)) \quad (16) \quad 45$$

Equation (16) gives the beats between the second harmonic of the signal, (1) and the oscillator, (2). The depth of phase or frequency modulation is 2ϕ . Consequently, the intermediate frequency signal is

$$I.F. = K E^2 E_0^2 \cos(\omega t - 2\phi \cos \omega t) \quad (17) \quad 55$$

Of course, if the Nth order of frequency multiplication were used, the 2ϕ would be replaced by $N\phi$.

After the radio frequency energy has been 60 heterodyned by the frequency multiplying detector, it is amplified at intermediate frequency and passed to the artificial line type of frequency modulation circuit.

In describing the manner in which the frequency modulated waves of increased modulation depth in the output of 5 are demodulated, it 65 must be kept in mind that conversion of the frequency modulations depends upon the fact that the electrical length of a filter or transmission line, such as 26, which consists of a series of sections composed of inductive, capacitive and/or resistive elements in a series and/or parallel arrangements or any one of a combination of said elements in said arrangement, varies with the impressed frequency. In the following ex- 70 75

planation, a transmission line, such as 26, will be utilized, although it will be understood that a filter, such as a high pass, low pass, bandpass, band elimination, etc., may be used. If the line is a given number of wave lengths long for a predetermined frequency, at a higher frequency the electrical length will be greater and at a lower frequency the electrical length of the line will be less. The fact that this electrical length does change with frequency makes the phase at the output of the line change with respect to that at the input of the line, if the frequency of the signal transmitted by the line is varied. Consequently, if the signal impressed on the input of the line is combined with the signal at the output of the line, an adjustment of the line may be made, so that the phase difference at the voltage of the signal impressed on the input of the line and the voltage of the signal appearing on the output of the line increases as the degree of frequency modulation is increased. This phase difference will cause a variation in the amplitude of the resultant of the combined voltages, so that an amplitude modulation is formed which is truly characteristic of the frequency modulation of the original signal.

In the specific application, the control grids of the differential detectors 28 and 29 are energized in phase opposition from unretarded energy derived from the output of the intermediate frequency amplifier 5. The control grids of tubes 28 and 29 are simultaneously energized cophasally by energy derived from a selected point on the retard circuit 26. By properly selecting the tap on 26 the resulting amplitude modulations due to the combination of the energy from the two paths which is fed to the control grids of detectors 28 and 29 may be made 180° out of phase. The resultants of the phase displaced energies from the two paths on the control grids of 28 and 29 produce variations in the amplitude of the energy in the output of tubes 28 and 29 which are characteristic of the frequency modulations on the signal wave. The energy from the outputs of tubes 28 and 29 is supplied by way of couplings 40 and 41 to coupling tubes 30 and 31 and from the output of the coupling tubes 30 and 31 to indicator 20. If frequency modulated waves are to be received, the outputs of tubes 30 and 31 are connected in push-pull relation. If amplitude modulated waves are to be received, the outputs of tubes 30 and 31 are connected in parallel.

Another method of utilizing the higher order effect detector for this type of frequency multiplication and detection would be to tune the local oscillator to approximately the harmonic of the signal so that a heterodyne, between the fundamental of the local oscillator and a harmonic of the signal, is obtained. This type of operation utilizes terms (2), (4), (3), (6), etc. of Equation (10). With e_1 as the signal and e_2 as the local oscillator, terms (2), (3), etc., would be utilized. With e_1 as the oscillator and e_2 as the signal, terms (4), (7), etc., would be utilized. As an example with e_1 as the signal and e_2 as the local oscillator tuned to approximately twice the frequency of the signal, the development similar to that of Equations (11) to (17) gives the following heterodyne output:

$$70 J = a_2 b_1 e_1^2 e_2 \quad (\text{term (2) of Eq. (10)}) \quad (18)$$

$$J = a_2 b_1 E^2 E_0 [\sin((2w + w_1)t - 2\phi \cos pt) + \cos((2w - w_1)t - 2\phi \cos pt)] \quad (19)$$

Equation (19) is the same as (16) except for its amplitude and the fact that the beats are be-

tween $2w$ and w_1 instead of $2w$ and $2w_1$. Since the amplitude is proportional to $a_2 b_1$ instead of $b_1 b_2$ and E_0 instead of E_0^2 , the efficiency of this type of multiplication, where the oscillator is tuned to the harmonic, is greater than that where a harmonic of the oscillator beats with a harmonic of the signal.

Instead of performing the multiplying and heterodyning at the first detector as shown in Fig. 2, the second detector of a triple detection superheterodyne receiver might be used. That is, the radio frequency amplifier 2 of Fig. 2 could be the intermediate frequency amplifier of a superheterodyne receiver. Thus, the multiplying and heterodyning could be done at any frequency.

The principle of multiplying the received energy can be applied to the use of any type of frequency or phase modulation conversion circuit for use on either phase or frequency modulation.

A triode detector may be used in place of the pentode detector to produce the multiplying and heterodyning action. The higher order effects produce the same sort of harmonic beats in any type of detector.

It is understood that limiting or automatic volume control may be incorporated at any point in these receivers in order that signal variations may be minimized. Similarly, automatic frequency or tuning control may be applied to maintain the receiver in tune with the signal.

What is claimed is:

1. In a signal modulated wave energy demodulating means, a thermionic tube having a plurality of grid-like electrodes and a cathode, a source of oscillatory energy coupled to one of said grid-like electrodes, a circuit coupling another of said grid-like electrodes to a source of signal modulated wave energy, and means for biasing the grid-like electrodes in said tube negative relative to the potential of the cathode of said tube an amount such that the said tube operates to beat a harmonic of the wave energy with energy from said source of oscillatory energy.

2. Signal modulated wave energy demodulating means as recited in claim 1 including means for tuning said source of oscillatory energy to a frequency of the order of the harmonic frequency of the modulated wave energy.

3. In a frequency deviation multiplier, a thermionic tube having a plurality of grid-like electrodes a cathode and an anode, a source of oscillatory energy coupled to one of said grid-like electrodes, a circuit coupling another of said grid-like electrodes to a source of signal modulated wave energy, and means for biasing the grid-like electrodes in said tube to negative potentials relative to the cathode potential such that the said tube operates to beat a harmonic of the signal modulated wave energy with a harmonic of the fundamental oscillatory energy from said source.

4. Phase or frequency modulated wave energy signalling means comprising, means for increasing the frequency of said wave energy for increasing the depth of phase or frequency modulation on said wave energy, modulated wave energy demodulating means, a circuit having a sloping characteristic coupling said first named means to said modulated wave energy demodulating means, and a second circuit having a characteristic which slopes in a sense opposite to the sloping characteristic of said first circuit coupling said first named means to said demodulating means.

5. Phase or frequency modulated wave energy signalling means comprising, means for increasing the frequency of said wave energy thereby increasing the depth of modulation on said wave 5 energy, modulated wave energy demodulating means, a circuit including a filter having a sloping characteristic coupling said demodulating means to said first named means, a circuit including a filter having a flat topped characteristic coupled to said first named means, a circuit including said filter having a sloping characteristic coupled to said first named means, combining means coupled with the output of said last two circuits, and a coupling between said combining means and said demodulating means.

6. Phase or frequency modulated wave energy signalling means comprising, means for increasing the frequency of said wave energy for increasing the depth of phase or frequency modulation on said wave energy, modulated wave energy demodulating means, a circuit having a sloping characteristic coupling said first named means to said demodulating means, a second circuit having a characteristic which slopes in a sense opposite to the sloping characteristic of said first circuit coupling said first means to said demodulating means, and means connected with said demodulating means for combining the outputs of said circuits in phase or in phase opposition.

30 7. Signal modulated wave energy signalling means comprising, modulated wave absorbing and amplifying means, a demodulator and a source of local oscillations coupled to said amplifying means, said demodulator having an output, a frequency multiplier coupled to the output of said demodulator, a source of local oscillations and a demodulator coupled to said frequency multiplier, said demodulator having an output, an intermediate frequency amplifier coupled to the output of said last named demodulator, said intermediate frequency amplifier having an output, a pair of thermionic tubes each having a control grid and having their control grids connected in parallel and coupled to the output of said intermediate frequency amplifier, each of said tubes also having an output electrode, an additional thermionic tube having a control grid coupled to the output of one of said last named tubes, said additional tube also having an output electrode, an indicator, and means for coupling the output electrodes of said three tubes to said indicator.

8. In a frequency or phase modulated wave energy signalling system, wave absorbing and amplifying means, a demodulator and a source of local oscillations coupled to said amplifying means, said demodulator having an output, a frequency multiplier coupled to the output of said demodulator, a source of local oscillations and a demodulator coupled to said frequency multiplier, said demodulator having an output, an intermediate frequency amplifier coupled to the output of said last named demodulator, said intermediate frequency amplifier having an output, a pair of thermionic tubes each having a control grid connected to the output of said intermediate frequency amplifier, each of said tubes also having an output electrode, an additional thermionic tube having a control grid coupled by way of filters of sloping characteristic to the output electrode of one of said pair of tubes, said additional tube having an output electrode, a filter having a square topped characteristic coupled with the output electrode of the other of said pair of tubes and with the output electrode of said additional

tube, and an indicator coupled with both of said filters.

9. In a frequency or phase modulated wave energy demodulating system, wave absorbing means, an amplifier coupled thereto, a thermionic tube having a plurality of grid-like electrodes, a cathode, and an anode, a source of local oscillations coupled to one of said grid-like electrodes, a circuit coupling another of said grid-like auxiliary electrodes to the output of said amplifier, means for biasing the grid-like electrodes in said tube relative to the cathode to such potentials that said tube operates as a harmonic generator, an intermediate frequency amplifier having an input coupled to the anode of said tube, said intermediate frequency amplifier having an output, a circuit of considerable electrical reactance coupled to the output of said intermediate frequency amplifier, a pair of detector tubes each having a control grid, a circuit coupling the control grids of said detector tubes in phase opposition to the output of said intermediate frequency amplifier, and a circuit connecting the control grids of said detector tubes cophasally to said circuit of considerable electrical reactance.

25 10. In a frequency or phase modulated wave energy demodulating system, wave energy absorbing means, an amplifier coupled thereto, a thermionic tube having a plurality of grid-like electrodes, a cathode, and an anode, a source of local oscillations coupled to one of said grid-like electrodes, a circuit coupling another of said grid-like electrodes to the output of said amplifier, means for biasing the grid-like electrodes in said tube relative to the cathode to such potentials that said tube operates as a harmonic generator, an intermediate frequency amplifier having an input coupled to the anode of said tube, said intermediate frequency amplifier having an output, a transmission line coupled to the output of said intermediate frequency amplifier, a pair of detector tubes each having a control grid and an output electrode, a circuit coupling the control grids in said detector tubes in phase opposition to the output of said intermediate frequency amplifier, a circuit connecting the control grids of said detector tubes to a point on said transmission line, and an indicator coupled with the output electrodes of said detector tubes.

11. In a system for demodulating wave energy the frequency of which has been modulated in accordance with signals, means for multiplying the frequency of said wave energy to thereby multiply the degree or amount of frequency modulation of said wave energy, means comprising a plurality of paths for said wave energy, said paths being capable of passing all the frequencies of the wave energy to be demodulated, means connected with said first named means for impressing wave energy representative of said wave energy of multiplied frequency and multiplied degree or amount of frequency modulation on said paths, reactive elements in one of said paths, means for combining the waves passed by one of said paths with that passed by the other of said paths, and means for producing indications of the combined waves.

12. The method of receiving a frequency modulated wave which consists in multiplying the frequency of said frequency modulated wave to thereby increase its frequency and the degree of frequency modulation of the wave of increased frequency, deriving from said wave of increased frequency and increased degree of modulation a plurality of currents each varying in frequency in accordance with variations of the wave of mul-

tiplied frequency, passing the currents of all of said frequencies through two paths having different characteristics of transmission for said currents and combining the output currents of these 5 two paths in a detector to re-create the transmitted signals.

13. The method of receiving a frequency modulated wave which includes the steps of multiplying the frequency of said frequency modulated 10 wave to thereby increase the degree of frequency modulation of the resultant energy, deriving from

said wave energy of multiplied frequency a plurality of currents, each varying in frequency in accordance with variations in said energy of multiplied frequency, passing each of the derived currents through a path, causing one of said paths to change the phase of the current passing therethrough with respect to that of the current passed by another path and combining the output currents of these two last mentioned paths in a detector to re-create the transmitted signal. 5
